CLAIM

The ornamental design for a bottle opener, as shown and described.

DESCRIPTION

FIG. 1 is a perspective view showing a first embodiment of a bottle opener showing my new design; FIG. 2 is a top view of the bottle opener of FIG. 1; FIG. 3 is a bottom view of the bottle opener of FIG. 1; FIG. 4 is a front view of the bottle opener of FIG. 1; FIG. 5 is a rear view of the bottle opener of FIG. 1; FIG. 6 is a side view of the bottle opener of FIG. 1; FIG. 7 is a perspective view showing a second embodiment of the bottle opener; FIG. 8 is a top view of the bottle opener of FIG. 7; FIG. 9 is a bottom view of the bottle opener of FIG. 7; FIG. 10 is a front view of the bottle opener of FIG. 7; FIG. 11 is a rear view of the bottle opener of FIG. 7; and, FIG. 12 is a side view of the bottle opener of FIG. 7. The broken lines are included to show portions of the bottle opener that form no part of the claimed design.
